US00D772642S

(12) **United States Design Patent** (10) **Patent No.:** **US D772,642 S**
(45) **Date of Patent:** **** Nov. 29, 2016**

(54) **BLENDING APPLIANCE**

(71) Applicant: **WHIRLPOOL CORPORATION**,
Benton Harbor, MI (US)

(72) Inventors: **Zachary A. Lownds**, St. Joseph, MI
(US); **Brandon T. Mock**, St. Joseph,
MI (US)

(73) Assignee: **Whirlpool Corporation**, Benton
Harbor, MI (US)

(**) Term: **15 Years**

(21) Appl. No.: **29/546,747**

(22) Filed: **Nov. 25, 2015**

Related U.S. Application Data

(62) Division of application No. 29/484,921, filed on Mar.
14, 2014, now Pat. No. Des. 744,275.

(57) **CLAIM**

We claim the ornamental design for a blending appliance, as shown and described.

DESCRIPTION

FIG. 1 is a front perspective view of a blending appliance of the present disclosure;

FIG. 2 is a rear perspective view of the blending appliance of FIG. 1;

FIG. 3 is a front elevational view of the blending appliance of FIG. 1;

FIG. 4 is a rear elevational view of the blending appliance of FIG. 1;

FIG. 5 is a first side elevational view of the blending appliance of FIG. 1;

FIG. 6 is a second side elevational view of the blending appliance of FIG. 1;

FIG. 7 is a top plan view of the blending appliance of FIG. 1; and,

FIG. 8 is a bottom plan view of the blending appliance of FIG. 1.

The broken lines shown in the drawings are for illustrative purposes only and form no part of the claimed design.
